CLAMP

Albert Dawson, Lake Worth, Fla.

Application February 26, 1934, Serial No. 713,037

1 Claim. (Cl. 76—78)

This invention relates to clamps and has as its object the provision of a clamp for supporting and securing a hand saw in position to facilitate the filing of the saw.

5 An object of the invention is to provide a clamp of this character which may be readily and detachably mounted on one end of a work bench and which will positively secure a hand saw, or a saw blade of any known description in position to facilitate the filing of the teeth of the saw.

A still further object of the invention is to provide a clamp of this character consisting of relatively few parts and which can be economically constructed and sold for a nominal price.

15 The invention together with its objects and advantages will be best understood from a study of the following description taken in connection with the accompanying drawings wherein:

Figure 1 is a top plan view illustrating the 20 application of the clamp.

Figure 2 is a side elevational view thereof.

Figure 3 is a sectional view taken substantially on the line 3—3 of Figure 2.

Figure 4 is an elevational view of one end of 25 the clamp.

Figure 5 is an elevational view of an opposite end of the clamp.

Figure 6 is a perspective view of one of the 30 members of the clamp.

Figure 7 is a perspective view of the other member of the clamp, and

Figure 8 is a fragmentary detail sectional view illustrating certain details to be hereinafter more fully pointed out.

35 Referring to the drawings by reference numerals it will be seen that the clamp comprises two cooperating clamp members 10, 11 each of which is formed of angle iron and has a portion thereof at one end extended and rolled upon itself to provide a hinge eye 12. Secured to the

40 hinge eye 12 of the clamp member 10 is a hinge pin 13 with which is engaged the hinge eye 12 of the clamp member 11 for hingedly connecting the members. At the free end thereof the clamp member 10 is tapered as at 14 and is rolled upon

45 itself to provide a spring clip or catch member 15 with which the free end of the clamp member 11 is engageable for securing the clamp members 10, 11 in clamping relation with the blade of a saw or the like clamped therebetween.

The flange 10a of the clamp member 10 is adapted to overlie a work bench or other suitable support 16, and at the end thereof the flange 10a is provided with anchoring prongs 17 that are 50 adapted to be embedded in the top of the table or bench 16 in the manner suggested in Figures 4 and 5 for securing the clamp to the table. The prongs 17 are formed in any suitable manner,

preferably by slitting the flange 10 and bending a portion of the flange adjacent the slit at right angles to the body of the flange, and then shaping these bent portions to points.

5 For suitably spacing the clamp member 10 from the end edge of the bench 16 said member 10 on one side thereof is provided with fixed lugs or projections 18 that are adapted to be placed against the end edge of the bench 16 in a manner clearly shown in Figure 5.

10 At the hinged end thereof the clamp member 11 has its vertical flange tapered or beveled as at 19 to accommodate the handle 20 of the saw when the blade 21 of the saw is clamped between the members 10 and 11 as will be clear from a 15 study of Figure 2.

In actual practice the clamp is secured to one end of the work bench 16 in the manner hereinbefore described in detail; the blade 21 of the saw is placed between the clamp members 10, 11 20 with the handle 20 disposed at the hingedly connected ends of the clamp members and will be secured between the clamp members when the clamp member 11 is swung from the dotted line position shown in Figure 1 to the full line position 25 shown in Figures 2 and 3 and the free end edge of the member 11 engaged with the spring keeper 15 of the stationary clamp member. It will be apparent that with the saw thus secured by the clamp the toothed edge thereof is disposed upwardly and the arrangement is such that a filing of the teeth can be readily and quickly accomplished.

30 It will be further understood that in actual practice the eye 12 will be of a length sufficient 35 to permit vertical or up and down movement of the clamp member 11 with sufficient freedom so as not to bend the hinge pin 13.

Having thus described my invention, what I 40 claim as new is:

In a saw clamp, a pair of jaws hingedly connected together at one end and provided at the end thereof opposite to the hinge with inter-engaging means for releasably securing the jaws in substantial parallel clamping position, said jaws 45 being constructed of angle iron to provide vertically disposed parallel flanges and a horizontal flange at the upper edge of each vertical flange projecting respectively in an opposite direction, and the horizontal flange of one of said jaws 50 having pressed therefrom penetrating prongs for piercing engagement with a support, and the vertical flange of said one jaw being also provided with spaced lugs to engage an edge of the support for spacing the vertical flanges of the jaw 55 from said edge of the support.

ALBERT DAWSON.
